US00D616853S

(12) **United States Design Patent**
Ahn et al.

(10) **Patent No.:** **US D616,853 S**
(45) **Date of Patent:** **** Jun. 1, 2010**

(54) **MOBILE PHONE**

(75) Inventors: **Chi-Young Ahn**, Seoul (KR);
Young-Keun Lee, Seoul (KR);
Chang-Hwan Hwang, Goyang-Si (KR)

(73) Assignee: **Samsung Electronics Co., Ltd.**,
Suwon-Si (KR)

(**) Term: **14 Years**

(21) Appl. No.: **29/340,822**

(22) Filed: **Jul. 27, 2009**

(30) **Foreign Application Priority Data**

Jun. 5, 2009 (KR) 30-2009-0024838

(51) **LOC (9) Cl.** **14-03**

(52) **U.S. Cl.** ..... **D14/138 AD**

(58) **Field of Classification Search** ..... D14/138 R,
D14/138 AD, 138 AC, 138 C, 138 G, 191,
D14/203.1–203.8, 496, 138 AA, 138 AB,
